UNITED STATES PATENT OFFICE.

CUTHBERT MILLER BURNETT, OF SHIRLEY, ENGLAND.

CONSTRUCTION OF FERROCONCRETE WALLS AND THE LIKE.

1,237,999.

Specification of Letters Patent. Patented Aug. 21, 1917.

Application filed February 23, 1916. Serial No. 80,041.

To all whom it may concern:

Be it known that I, CUTHBERT MILLER BURNETT, civil engineer, a subject of the King of Great Britain, residing at St. Katharine's Clifton Road, Regents' Park, Shirley, in the county borough of Southampton, Eng., have invented certain new and useful Improvements in the Construction of Ferroconcrete Walls and the like, of which the following is a specification.

This invention relates to the construction and reinforcement of concrete walls of buildings and the like, and has for its object to provide means, namely, specially prepared forms, casings, or shutters, for holding or retaining plastic concrete in position during the process of constructing and until set, and means for holding the said forms in position during the operation of filling, and for retaining them in position until the concrete is set.

To the above end my invention is characterized by the employment of a plurality of shutters or form sections which are made to a suitable standard size or sizes. These shutters may be constructed of wood or iron or of cement and asbestos sheets of the kind known as "Eternit," or "Fibro cement" or the like, backed or reinforced with wood or other suitable substance; or they may be made of the material known as jointless flooring, or other material reinforced internally with wire or the like, or covered with canvas or the like externally. According to my invention the shutters are fitted at intervals on their top and bottom edges or otherwise with hooks so constructed that when required they may be operated to release their hold on the attachment which connects the shutter of which they form part to the opposite shutter. The hooks preferably project beyond the inner face of the shutter or otherwise.

The method of carrying out my invention for constructing concrete walls is as follows: I first strain, by mechanical or other means, wires or other suitable reinforcements horizontally along the fixed site of the wall at distances apart equal to the width of the shutter, that is, equal to the vertical distance apart of the releasable hooks, or in some other suitable position. To these wires or reinforcements there are attached by

suitable means at points opposite the releasable hooks metal or other loops or attachments which are fitted at the shutter ends with eyes or attachments which engage with the releasable hooks on the shutters. These loops have the effect of holding the shutters at the required distance away from the reinforcements, and the required distance away from each other. In another form of the invention the loops are releasably attached to the back of the shutters, as in Figures 7, 8, and 9, hereafter illustrated.

Having thus generally described the object, nature, and effects of the invention, I will now proceed to describe it with reference to the accompanying drawings. The examples which I have illustrated show arrangements and constructions of parts according to this invention. In the various figures the same parts are designated by the same letters, and they correspond with those used in the following explanation.

The accompanying drawings are given solely by way of examples for the purpose of showing how the loops may be releasably attached to the shutters, and also how the loops may be attached to the reinforcements; their effectiveness in supporting the shutters in their required position being mainly dependent on the strained or semi-rigid pilot wires or reinforcements, and therein lies one of the principal points of my invention.

With reference to the accompanying drawings, Figs. 1, 2, and 3, relate to one method of obtaining the object of this invention.

Figs. 4 and 5 show another method, and Figs. 7, 8, and 9, illustrate still another method.

Fig. 1 is a sectional elevation of a pair of shutters ready for filling, also showing the top edge of a pair of shutters already filled with concrete.

Fig. 2 is a plan view of part of a pair of shutters showing the releasing hooks, reinforcement and connecting loop in position.

Fig. 3 is an elevation of the back of a part of a shutter, showing cranked spindles for actuating the releasing hooks, and hooks for retaining the spindles in a fixed position during the filling of the shutters.

Fig. 4 is a sectional elevation of a pair of shutters ready for filling, the means for releasing the shutter in this case being a

hinged bar provided with hooks at the top and bottom.

Fig. 5 is an elevation of the back of part of a shutter showing the hinged bar and 5 clips for holding the bar in position.

Fig. 6 is a sectional plan of the bar and clip.

Fig. 7 is a plan of part of a pair of shutters, showing the reinforcement and loop 10 attached to the shutters by means of thumb screws which take the place of the hooks used in the other forms of the invention.

Fig. 8 is a sectional elevation of Fig. 7.

Fig. 9 is an elevation of the back part of 15 a shutter equipped with the thumb screws.

Like characters denote similar and like parts throughout the specification and drawings.

With particular reference to Figs. 1 to 3, a 20 denotes the shutters or sections of the form comprising a facing member a^1 of sheet material such as asbestos, iron sheeting or the like, and a frame or backing a^2 which may be of wood or other suitable material. 25 Secured to the frame of each section and adjacent its top and bottom edges are the bars or spindles b^1 which are rotatably mounted in the cleats b^2 . The inner end of each bar is bent at an angle to the remaining portion 30 so as to provide a suitable handle for rotating the bar about its axis. The outer ends of the bars b^1 have secured thereto the hooks b , said hooks projecting laterally therefrom and accommodated in recesses formed in the 35 top and bottom edges of each section a , so that they will not protrude beyond the edges thereof but lie substantially flush therewith. In setting the form sections up, and after the reinforcing members d have been 40 stretched or laid in the manner before mentioned, use is made of the connecting or spacing loops c . Each of these loops c preferably comprises an elongated plate having a central opening c^1 in which the corresponding reinforcing member d engages and 45 having openings c^2 in the opposite ends thereof in which engage the bills of the hooks b , as shown in Figs. 1 and 2, said bill portions having their curved inner or engaging 50 edges disposed eccentrically of the axes of rotation of the bars or spindles b^1 , so as to exert a wedging or binding action upon the ends of the loop when the latter is rotated in one direction by means of its bar or 55 spindle, and to immediately release the loop ends when rotated in the other direction. It will be clear from Fig. 1 that in erecting the form in accordance with the invention, the reinforcing members d are first laid at 60 a relative distance apart equal to the width of each section of the form. The loops c are then disposed on the reinforcing members and the sections a are arranged in place in the manner shown, with their hooks b moved

to engage in the openings c^1 of the spacing or 65 loop members c . After one section of the form has been filled it may be built upon in the manner shown, the lower hooks b of the added form sections engaging in the openings c^1 of the uppermost spacing member c of the lower adjacent sections. In this way, the form may be built up as the work progresses and since the spacing members c remain permanently embedded in the concrete the form sections are held rigidly during the course of the work.

Provision is made for locking the hooks b in engagement with the spacing members c , by means of retaining hooks b^3 which lock over the handle portions of the bars b^1 to 70 prevent them from rotating. When it is desired to knock down the sections, it is only necessary to release the retaining hooks b^3 and to rotate the bars b^1 so as to move the hooks b from engagement with the spacing members c .

In Figs. 4 and 5 a modified form of the invention is shown, the modification consisting mainly in a varied construction of the means for retaining the shutters or form sections a in position. According to Figs. 4 and 5, each of the spacing members c consists of a wire looped around the reinforcing members d and having its outer ends provided with eyes in which engage the hooked outer ends b of a pair of vertical fastening bars b^1 hinged together at b^4 at their confronting inner ends, these bars, when arranged in position, having their free ends extended through the cleats b^2 , secured to the form section. Pivoted retaining members b^3 are also provided for retaining the hinged bars in position and, when it is desired to remove said bars, the retaining members b^3 are moved from engagement therewith so that the hooks b may be released from the spacing members c by the breaking of the hinged joints b^4 of said bars. The loop members c have spurs c^3 thereon which are formed by shearing and depressing a portion of the members c . The spurs c^3 temporarily retain the shutters in an upright position during the assemblage of the form sections and also form anchors for the reinforcing members of the concrete construction.

In Figs. 7, 8, and 9, a still further modification of the section fastening means is shown. In this embodiment the opposite ends of the loops or spacing members c are provided with eyes bent at right angles to the body of said members, so as to lie opposite the outer face of the form sections, as will be clearly seen from Fig. 8. Thumb screws b^6 are extended through the eyes of the members c and are removably threaded in the plates b^5 secured on the frame a^2 of the form section a .

In both embodiments shown in Figs. 4, 5,

6, 7, 8, and 9, the upper and lower edges of each form section are suitably recessed to provide spaces through which the ends of the loops or spacing members *c* extend. It is to be understood that in erecting the form, according to the invention, the reinforcing members *d* have their ends anchored to beams or uprights and are thus held taut or in a semi-rigid condition. The form sections shown in the modifications may be built up in substantially the same manner as the sections shown in Figs. 1, 2 and 3.

The wires or reinforcements together with the loops hold the shutters or form sections in position while the intervening space between the shutters is filled with plastic concrete, the reinforcements and loops being built in with the concrete and after the concrete has become set form permanent parts 20 of the wall. When the concrete is sufficiently set the hooks are released and the shutters removed.

My invention provides a simple and inexpensive wall for houses, stores and other buildings, garden and retaining walls and the like, which by these means can be constructed of any desired thickness, the length of the loops being the determining factor. The invention is also suitable for the side 30 shuttering of beams and the casting of lintels, posts, and the like.

Having thus described my invention, what I claim as new therein, and desire to secure by Letters Patent is:—

35 1. Apparatus for constructing reinforced concrete walls and the like, comprising, in combination, a pair of spaced form sections adapted to receive the plastic concrete therebetween; means for holding a reinforcement 40 under tension in the space between the form sections; a loop arranged transversely in said space and secured intermediate its ends to the tensioned reinforcement, to hold said form sections in spaced relation, said loop 45 being maintained in a comparatively rigid position by the tension of the reinforcement; and retaining means carried by said form sections and engaging the opposite ends of said loop.

50 2. Apparatus for constructing reinforced concrete walls and the like, comprising, in combination, a pair of spaced form sections adapted to receive the plastic concrete therebetween; a reinforcement wire extending 55 longitudinally of the space between said form sections; means for holding said wire under tension; a loop arranged transversely in said space and secured intermediate its ends to said wire, to hold the form sections 60 in spaced relation, said loop being maintained in a comparatively rigid position by the tension of the wire; and retaining means carried by said form sections and releasably engaging the opposite ends of said loop.

3. Apparatus for constructing reinforced 65 concrete walls and the like, comprising, in combination, a pair of spaced form sections adapted to receive the plastic concrete therebetween; a loop arranged transversely in the space between the form sections; a 70 rotatable member arranged against the outer face of each form section; a hook carried by each of said members for releasable engagement with the adjacent end of the loop; and means associated with said members 75 for locking said hooks in engaged position.

4. Apparatus for constructing reinforced concrete walls and the like, comprising, in combination, a pair of spaced form sections adapted to receive the plastic concrete there- 80 between; a loop arranged transversely in the space between the form sections; a rotatable handle-carrying bar arranged against the outer face of each form section; a hook carried by each bar for releasable engage- 85 ment with the adjacent end of the loop; and locking means engageable with the bar han- dles to retain the hooks in engaged position.

5. Apparatus for constructing reinforced 90 concrete walls and the like, comprising, in combination, a pair of spaced form sections adapted to receive the plastic concrete there- between; a loop arranged transversely in the space between the form sections; and a 95 vertical bar arranged against the outer face of each form section for movement with respect thereto, each bar being provided at its upper end with a hook which is alterna- 100 tively engaged with or released from the adjacent end of the loop consequent upon the movement of the bar.

6. Apparatus for constructing reinforced concrete walls and the like, comprising, in combination, a pair of spaced form sections 105 adapted to receive the plastic concrete therebetween; a loop arranged transversely in the space between the form sections; hooks rotatably carried by said form sec- 110 tions and provided with bills for releasable engagement with the ends of said loop, said bills being arranged eccentrically of the axes of rotation of said hooks so as to exert a 115 wedging action upon the loop ends when the hooks are rotated in one direction, and to immediately release said loop ends when rotated in the other direction; means carried by said form sections for rotating said hooks; and means associated with said rotating means for locking said hooks in en- 120 gaged position.

7. Apparatus for constructing reinforced concrete walls and the like, comprising, in combination, a pair of spaced form sections adapted to receive the plastic concrete there- 125 between; a loop arranged transversely in the space between the form sections, hooks rotatably carried by said form sections and

provided with bills for releasable engagement with the ends of said loop, said bills being arranged eccentrically of the axes of rotation of said hooks so as to exert a wedging action upon the loop ends when the hooks are rotated in one direction, and to immediately release said loop ends when rotated in the other direction; a rotatable handle-carrying bar individual to each hook and whereon the same is mounted, said bars

being carried by said form sections; and means engageable with the bar handles for locking said hooks in engaged position.

In testimony whereof I have hereunto set my hand in presence of two subscribing witnesses.

CUTHBERT MILLER BURNETT.
